UNITED STATES PATENT OFFICE.

FRANK E. MASON, OF SOUTH WHITLEY, INDIANA.

STOVEPIPE-FASTENER.

SPECIFICATION forming part of Letters Patent No. 746,122, dated December 8, 1903.

Application filed November 1, 1902. Serial No. 129,726. (No model.)

To all whom it may concern:

Be it known that I, FRANK E. MASON, a citizen of the United States, residing at South Whitley, in the county of Whitley and State of Indiana, have invented a new and useful 5 Stovepipe-Fastener, of which the following is a specification.

This invention is an improved device for securing the end of a stovepipe in the thimble for the purpose of preventing the accidental displacement of the said stovepipe end; and the object of the invention is to provide a device which can be used in connection with various sizes of thimbles and stovepipes, said 15 device being adjustable within certain limits, whereby various sizes of thimbles and pipes are accommodated.

With this object in view the invention consists, broadly, of an expanding band adapted 20 to be arranged within the stovepipe-thimble, said band carrying a ring which is adapted to be secured to the stovepipe, preferably in advance of a ridge or corrugation formed upon the said pipe, thereby securely fastening the said pipe within the thimble.

The invention consists also in certain details of construction and novelties of combination, all of which will be fully described hereinafter, and pointed out in the claims.

30 In the drawings, Figure 1 is a perspective view showing the practical application of my invention. Fig. 2 is a longitudinal sectional view taken through the thimble and the end section of the stovepipe. Fig. 3 is a longitudinal sectional view looking in the opposite direction and more clearly illustrating the fastening device. Fig. 4 is a detail perspective view of the essential features of the invention. Fig. 5 is a detail perspective view of 35 the wedge-guide which is attached to the interior of the thimble.

In carrying out my invention I employ a metallic thimble A, the edges A' being turned over to securely fasten the thimble within the 45 opening.

B indicates the end section of the stovepipe, the fluted or corrugated end B' of which enters the thimble, and it is for this purpose of securing said end within the thimble that I 50 have devised my present form of fastener, which comprises a sheet-metal band C, divided at C', the ends being preferably cut

slightly upon the bias, said ends being adapted to engage the guideways D' of the wedge-guide plate D, which is securely riveted with 55 in the thimble. The band C is provided with three forwardly-projecting arms E, which are rolled back upon themselves at their outer ends, as shown at E', for the purpose of receiving and carrying a wire ring F, which is divided 60 at F', the ends being formed into eyes F', through which a bolt G is adapted to pass, said bolt having a head G', and the nut G' is adapted to be secured upon the threaded end 65 for the purpose of drawing together the ends of the ring and binding the said ring securely 70 around the stovepipe-section B, and in practice I prefer to have said pipe formed with an annular crimp or corrugation B', and whenever said annular crimp or corrugation is present the ring F is arranged in advance of 75 the same, as most clearly shown in Fig. 2.

In operation the band C is inserted within the thimble and the ends of said band brought into engagement with the wedge-plate D, and 80 by pulling outwardly upon the said band it is expanded, so as to bind tightly within the thimble. The end of the stovepipe is then inserted into the thimble and within the band, and ring and the bolt and nut are then applied, for the purpose of binding the ring securely around the stovepipe-section. After 85 all the parts have been thus connected it will be impossible for the stovepipe-section to become disconnected from the thimble.

Having thus fully described my invention, what I claim as new, and desire to secure by Letters Patent of the United States, is—

1. A stovepipe-fastener comprising a band having arms connected thereto, a ring carried by said arms, means for contracting said ring, a thimble within which the band is located and means connected to said thimble for the purpose of expanding the band, as 90 specified.

2. A stovepipe-band comprising a thimble having a wedge-shaped guide-plate secured thereto, a band arranged within the thimble, the ends of which are adapted to engage the guiding edges with the wedge-plate, arms 100 connected to said band, a ring carried by said arms and having eyes at its ends, and a bolt and nut for contracting said ring, for the purpose specified.

3. A stovepipe-fastener comprising a thimble, a wedge, having guide-flanges along its converging sides, secured to said thimble, a split band adapted to slide in said thimble, the ends of said band sliding between the guide-flanges of the wedge, and means connected to the band adapted to clamp a stovepipe.
4. The combination with a thimble flanged

at each end, of a split band adapted to slide in said thimble, means connected to the band for holding a stovepipe, and a wedge permanently secured to the thimble, and adapted to engage and force apart the edges of the band.

FRANK E. MASON.
